UNITED STATES PATENT OFFICE.

MURRAY E. PAGE AND THOMAS S. PAGE, OF SYRACUSE, NEW YORK.

FUEL BURNER.

Application filed December 21, 1923. Serial No. 632,071.

To all whom it may concern:

Be it known that we, MURRAY E. PAGE and THOMAS S. PAGE, citizens of the United States of America, residing at Syracuse, in the county of Onondaga and State of New York, have invented certain new and useful Improvements in Fuel Burners, of which the following is a specification.

This invention relates to certain new and useful improvements in fuel burners and particularly to a burner of the retort type wherein liquid fuel being delivered to a burner nozzle is adapted to pass through a retort casing overlying the burner nozzle to effect preheating and vaporization thereof before passing to the burner nozzle.

Another object of the invention is to provide a fuel burner of the retort type wherein a retort casing overlying a burner nozzle carries a protuberance or projection of increased cross-sectional area upon the lower side thereof adjacent the burner nozzle to absorb the maximum quantity of heat from the nozzle for preheating and vaporizing the liquid fuel in the retort chamber prior to its delivery to the burner nozzle.

The invention further provides a settling chamber in the retort of the burner for the collection of a quantity of the liquid fuel in its passage through the fuel supply pipe to the burner nozzle whereby a greater quantity thereof may be preheated and vaporized prior to its discharge and ignition at the discharge burner nozzle.

With the above and other objects in view that will become apparent as the nature of the invention is better understood, the same consists of the novel form, combination and arrangement of parts hereinafter more fully described, shown in the accompanying drawing and claimed.

In the drawing, wherein like reference characters designate corresponding parts throughout the several views,

Figure 1 is a vertical side elevational view, partly shown in section of a fuel burner constructed in accordance with the present invention, showing the enlarged retort chamber overlying the burner nozzle with the drip pan disposed below the nozzle and retort,

Figure 2 is a horizontal sectional view taken on line II-II of Fig. 1, and

Figure 3 is a bottom plan view of the retort.

In the accompanying drawing which

shows the preferred embodiment of the present invention, the reference numeral 5 designates a fuel pipe having a threaded lower end 6 adapted for connection with an ordinary type of fuel supply pipe that is valve controlled in any preferred manner, the fuel pipe 5 being externally threaded from its lower end upwardly, as at 7, intermediate the upper and lower ends thereof and freely passing through an opening 8 provided in the plate 9 that extends laterally therefrom and is preferably of the configuration in plan view as illustrated in Fig. 2. The plate 9 is retained in position upon the fuel pipe 5 by the nuts 10, respectively positioned above and below the plate and engaging the threads 7 on the supply pipe for rigidly supporting the plate 9 in position thereon.

A retort in the form of a hollow casing is associated with the upper end of the fuel pipe 5 and embodies upper and lower walls 11 and 12 respectively, and end walls 13 and 14. An elbow 15 is mounted on the threaded upper end 16 of the fuel pipe 5 and carries a reduced threaded stem 17 at its other end that is threaded into the internally threaded outwardly extending boss 18 carried by the end wall 13 of the retort casing. The bottom wall 12 of the retort casing carries a depending projection or protuberance 19 at the central portion thereof providing an area of increased cross-section as illustrated in Fig. 1 for purposes presently to appear.

A vertical pipe section 20 is associated with the end wall 14 of the retort casing, the same being disposed above the plate 9 with an elbow 21 threaded upon the upper end thereof and carrying a reduced threaded stem 22 that is threaded into the outwardly directed tubular boss 23 carried by the end wall 14 of the retort casing. An elbow 24 is threaded on the lower end of the pipe section 20 with the lower side of said elbow resting in the cavity 25 formed in the upper side of the plate 9 adjacent the outer end thereof to constitute a support for the pipe section 20 and the adjacent end of the retort casing. The upper face of the plate 9 is provided with a relatively large cavity 26 constituting a drip pan and over which the short pipe section 27 threaded into the adjacent end of the elbow 24 is disposed.

The burner head includes an elbow 28 having the pipe section 27 threaded into one end thereof with the elbow 28 perpendicularly

- positioned as illustrated, the upper end thereof being slightly reduced and externally threaded for the reception of a screw cap 29 having a central burner jet opening 30.
- 5 The burner head is disposed directly beneath the protuberance or projection 19 depending from the lower wall 12 of the retort casing and the flame issuing from the burner jet opening 30 is directed against said protuberance to convey the greatest possible amount of heat thereto. Liquid fuel passing through the fuel pipe 5 enters the retort casing and settles in the lower end thereof to the horizontal level of the elbow attaching stems 17 and 22, thereafter flowing through the elbow 21, pipe 20, elbow 24 and pipe section 27 to the burner head 28 to overflow through the jet opening 30 and drips into the drip pan 26. The fuel in the 10 drip pan 26 is ignited to heat the burner head 28 at the time of starting the burner, and when the temperature of the burner head 28 has been sufficiently raised, a jet flame will issue through the burner opening 30 and be directed toward the retort casing. The liquid fuel in the retort casing is then heated to the point of vaporization and the vapor or gas passes through the several pipe and elbow sections to the burner head. The depending projection or protuberance 19 being of increased cross-sectional area, absorbs a greater amount of heat with consequent greater radiation and heating of the liquid fuel in the retort casing 15 thereby insuring more complete vaporization of the liquid fuel in the retort casing prior to delivery thereof to the burner head. Also, by the provision of the depending protuberance upon the bottom wall of the retort casing, with the flame from the jet nozzles directed thereagainst, the usual noise resulting from combustion, is considerably reduced and the hissing sounds generally
- 20 25 30 35 40

present in burners of this character are practically eliminated.

45 While there is herein shown and described the preferred embodiment of the present invention, it is nevertheless to be understood that minor changes may be made therein without departing from the spirit and scope 50 of the invention as claimed.

What is claimed as new is:—

55 1. In a burner of the class described, a vertically disposed fuel supply pipe having its lower portion screw threaded, an elbow carried by the upper end of said pipe, a retort connected to the elbow, a drip pan mounted on the threaded portion of the fuel supply pipe to move vertically thereon, adjusting nuts on said threaded portion of the fuel supply pipe above and below the drip pan to adjust the position of the latter on the fuel supply pipe, a burner head supported by the drip pan, and a pipe connection between the burner head and retort.

60 65 70 75 80 85 90 95 2. In a burner of the class described, a vertically disposed fuel supply pipe having its lower portion screw threaded, an elbow carried by the upper end of said pipe, a retort connected to the elbow, a drip pan mounted on the threaded portion of the fuel supply pipe to move vertically thereon, adjusting nuts on said threaded portion of the fuel supply pipe above and below the drip pan to adjust the position of the latter on the fuel supply pipe, a burner head supported by the drip pan, and a pipe connection between the burner head and retort, said drip pan having a drip recess wherein the lower part of said pipe connection rests and being laterally extended on each side thereof to provide heat conserving means.

In testimony whereof we affix our signatures.

MURRAY E. PAGE.
